UNITED STATES PATENT OFFICE.

PERLEY R. GLASS, OF QUINCY, MASSACHUSETTS, ASSIGNOR TO PEERLESS MACHINERY COMPANY, OF CHARLESTOWN, WEST VIRGINIA, AND NEW YORK, N. Y.

NAILING APPARATUS.

SPECIFICATION forming part of Letters Patent No. 695,385, dated March 11, 1902.

Application filed December 17, 1900. Serial No. 40,080. (No model.)

To all whom it may concern:

Be it known that I, PERLEY R. GLASS, a citizen of the United States, residing at Quincy, county of Norfolk, State of Massachusetts, have invented an Improvement in Nailing Apparatus, of which the following description, in connection with the accompanying drawings, is a specification, like characters on the drawings representing like parts.

10 In another application, Serial No. 34,877, filed October 30, 1900, I have shown and described a nailing apparatus having a hopper which may be rotated while the driver is inoperative to load the raceway with tacks.

15 The invention to be herein described is intended to be an improvement on the apparatus shown in said application.

One feature of invention herein contained is a provision for stopping or starting the 20 shaft carrying the pinion employed to rotate the hopper, I using, as herein shown for such purpose, a clutch. I have also produced a novel pick-off and stop, it presenting double points to better control the nail or tack. I 25 have also devised a novel clearer to dislodge any nails or tacks improperly deposited upon the raceway.

Figure 1, in side elevation, represents a nailing-machine hung up in its inoperative position that its raceway may be filled. Fig. 2 is a view looking at the hanger and its driving mechanism from the left, Fig. 1. Fig. 3 is a section through the apparatus, raceway, and hopper. Fig. 3^a is a detail of the upper end 30 of the raceway. Fig. 4 is a detail showing the pick-off, nose, and driver in one of its positions. Figs. 5 and 6 show the pick-off from its side nearest the end of the raceway and the nose, the pick-off being in different 35 positions. Fig. 7 shows the pick-off in perspective; and Fig. 8 is a section in the line x, Fig. 3.

The frame or hand piece A presents a tube having an extension A', which may be provided, as shown, with a stud A², which may enter notches of a bracket or wall piece B, adapted to be secured to any suitable support, as a wall, by a screw. The extension also serves to sustain the raceway C and 45 hopper G, to be described. The tubular part of the frame contains a bearing a for a driver-

bar a', having a driver a³, said driving-bar having at its upper end a shouldered head a², provided with a depending tube a³, which, as shown, enters the tubular part of the frame. 55 A spring a⁴, resting at one end on the bearing a and acting at its other end against the head, keeps the driver-bar normally in its inoperative position. The extent of movement of the bar a' by the spring a⁴ is controlled by a stop a⁵, which enters a slot a⁶ in the bar. The driver-bar has at its lower end a finger a⁷, which at each descent of said bar meets a roller or other stud e of a slide E, a suitable spring, as e', moving the said slide in the opposite direction. 65

The nose D, inserted in the lower end of the tube A, is grooved transversely to sustain and guide the substantially U-shaped slide E in its movements, and said nose is also 70 notched to sustain the lower end of the raceway C, as shown in Fig. 3. The lower end of the raceway enters the open space e² between the arms of the slide, and the groove of the said raceway, in which hang the bodies of 75 the nails, is in line with a slot in the side of the nose, that nails may enter the nail-passage d' in said nose. In order that the nails may enter the nose singly to be acted upon by the driver, each arm of the slide is provided with two prongs, the said prongs constituting two pairs of oppositely-disposed prongs facing each other, each arm of the slide carrying one prong of each pair. The 80 said prongs are separated to leave a diagonal 85 space between the contiguous ends of each pair through which each nail taken from the end of the raceway by said prongs passes on its way into the driver-passage. By the employment of the lower pair of prongs e⁵ e⁶ 90 it becomes possible to control and position the point or lower end of the nail, whatever its length, and prevent it from tipping on the upper side of the prongs e³ e⁴, so that the point of said nail will meet the nose in the 95 bottom of the slot therein through which the nail enters the nose. The nose has a vertical slot d², in which is pivoted a nail-supporting device d³, acted upon by a spring d⁴, which normally keeps the hooked lower end of said 100 device in position to arrest each nail picked off the raceway by the slide E until said nail

is struck by the driver. The raceway, composed of a bar having a suitable slot or groove, is held in place by suitable screws c' , other screws c^2 holding in place the cover c^3 in usual manner. The upper end of the raceway entering the hopper G has a wing c^4 , on which the nails lifted by the shelves g of the hopper drop, the points of the nails entering the groove of the raceway, while the heads of the 50 nails are sustained thereby. The inner end of the hopper has a flange g' , which enters a circular groove between a ring g^2 and a circular plate g^3 , preferably forming a part of the frame-casting. The inner or left-hand side 10 (see Fig. 3) of said ring and casting has also, as shown, a circular guideway or groove, which, as shown, receives a series of carriage-blocks g^4 , connected with said hopper by suitable screws g^5 , said carriage-blocks and the 15 end of said hopper traveling in said circular grooves as the hopper is rotated. By supporting the foot of the hopper at one end in a circular groove I obviate the employment of a shaft extended centrally through the hopper, and the space inside the hopper is less obstructed, enabling the diameter of the hopper to be reduced. The hopper has connected with it by suitable screws g^6 a toothed ring g^7 . The right-hand end of the hopper is provided 20 with a door g^8 , sustained by suitable hinges g^9 . The casting g^3 has pivoted to it at h a clearer h' , shown as a spring-controlled lever having its upper end inclined (see Fig. 8) to be struck by a series of rollers or other studs 25 m , carried by screws m' , inserted in the flange g' , the lower curved end of said clearer extending transversely to the raceway and being vibrated opposite the stress of the spring 30 2 and occupying always a position above the raceway just above the upper end of the cover, the clearer acting as a gage to enable the heads of nails properly seated in said raceway to descend and by its curved lower end removing from the raceway any nails or tacks 35 lodged thereon improperly.

To prevent a nail lodged crosswise on the raceway from entering the space between the under side of the clearer, occupying always a position over the raceway, and the top of the 40 raceway, I have erected on the side of the raceway a stop 10, (see Fig. 3^a, full lines, and Fig. 3, dotted lines,) the upper end of said stop extending above said raceway and arresting such nails.

55 The clearer, in order that it may operate properly and not be subjected to lateral strain to thereby bind the clearer on or strain the pivot h , is guided at its lower end by means of a stud m^2 , the shank of which is extended 60 through a slot in the plate g^3 and enters the clearer, the head of the stud moving close to the said plate. By extending the head of the clearer through the slot in the plate g^3 the said clearer may be manually vibrated by 65 means of the stud m^2 should the said clearer stick or get caught.

When the operator commences to use the

apparatus, he holding it in one hand, the raceway is supposed to be filled up with nails or tacks, and while the apparatus is used in driving 70 nails the hopper is usually at rest.

When the apparatus is not being used, as when, for instance, a workman is preparing a shoe to receive nails or tacks for lasting or for other purpose, the workman hangs the 75 frame upon the bracket B , as in Fig. 1, so that the toothed ring g^7 is put in mesh with the pinion H on a shaft H' , having its bearing in said bracket and provided at its opposite end with a bevel-gear H^2 , which is engaged and driven by a bevel-gear H^3 on a main shaft H^4 , provided, as herein shown, with a belt-wheel J , loose thereon, and provided with a stud 3, forming part of a clutch, the other part being a stud 4, carried by a block J' , having a pin 5, entering loosely a slot 6 in the shaft H^4 . By the employment of this clutch it is possible when in the position Fig. 2, the clutch being separated, to enable the pulley J to be run, it being driven by a belt (not 80 shown) actuated by a pulley from any usual counter-shaft without rotating the shaft H^4 and the hopper. When it is desired to rotate the hopper to fill the raceway, the clutch will be made operative by sliding the hub J' toward the hub of the pulley, and whenever the raceway has been filled the clutch will be 85 opened and the further rotation of the hopper 90 be stopped.

Having described my invention, what I 95 claim as new, and desire to secure by Letters Patent, is—

1. In a nailing-machine, a raceway, a hopper, a loosely-pivoted clearer inside the hopper, means carried by said hopper to vibrate 100 the clearer transversely of the raceway, a headed guide-pin connected to the clearer and projecting through a slot in the hopper, the head of said pin engaging the outside of the hopper and serving to maintain the clearer 105 in its operative position.

2. In a nailing-machine, a raceway, a cover therefor, a clearer having its lower end beveled, and means to move said clearer transversely of said raceway, and a stop independent from the raceway-cover, and secured to one side of and extended above said raceway to arrest a nail laid crosswise thereon, and prevent said nail from entering the space between the clearer and raceway.

3. In a nailing-machine, a raceway, a cover therefor, a clearer, means to move the said clearer transversely of the raceway, a stop secured to one side of the raceway and extended above the same, said stop being independent 125 from the raceway-cover and situated in the same plane as the clearer, the said stop operating to arrest a nail laid crosswise upon the raceway and the clearer operating to dislodge said nail from the raceway.

4. In a nailing-machine, a raceway, a hopper having external teeth, a shaft, a gear thereon, means to detachably sustain said hopper so that the teeth thereon will engage the

said gear, means to rotate said shaft when it is desired to rotate the hopper to fill the race-way, and a clutch to stop the rotation of said shaft and hopper when desired.

5. In a nailing-machine, a frame or extension having a circular groove, a hopper having at its periphery a flange seated in said groove, means to secure the flange in the groove, whereby the hopper is supported by

10 the flange, and means to rotate said hopper.

6. A hopper having a flange at one end, and

a series of carriage-blocks connected to said flange, combined with a frame having a circular groove in which said blocks travel as the hopper is rotated.

15 In testimony whereof I have signed my name to this specification in the presence of two subscribing witnesses.
